SULFONATE DETERGENT COMPOSITIONS OF IMPROVED FOAM CHARACTERISTICS

Henry Y. Lew, San Francisco, and Richard D. Stayner, Berkeley, Calif., assignors to California Research Corporation, San Francisco, Calif., a corporation of Delaware

No Drawing. Application June 29, 1956
Serial No. 594,702

3 Claims. (Cl. 252—152)

The present invention relates to improved sulfonate detergent compositions.

Among the variety of synthetic detergents available on the market and competing with soap for different laundering and industrial uses, the largest group is that of alkylbenzene sulfonate detergents. These highly efficient detergent sulfonates are prepared by known processes, for instance, by alkylating benzene with olefin polymers, preferably with polymers of propylene, in the presence of appropriate alkylation catalysts. The resulting alkylate is then sulfonated, the sulfonation product is neutralized with a base and, if desired, combined with builders, and finally, the neutralized material (slurry) is reduced by drying to the ultimate product form and size. In the finally obtained detergent product, the active alkylbenzene sulfonate material is formed by branched-chain C₉—C₁₅ monoalkylbenzene sulfonate, among which those containing C₁₂—C₁₅ alkyl chains usually preponderate. It is observed that aqueous solutions of these branched-chain monoalkylbenzene sulfonates, whether employed alone or in combination with the conventional detergent salt builders, when agitated in the washing machines or dishwashers, form at first large volumes of copious suds which rapidly collapse, however, under the conditions of agitation and in contact with soil, owing to a weak, lacy texture of these suds. This inability of producing satisfactory, stable, soap-like suds throughout the complete washing cycle represents a serious drawback in the eyes of a large fraction of the consumer public who often consider the foam to be an index of the washing efficiency and a measure of the washing material (soap or synthetic detergent) necessary for effective soil removal.

A large number of compounds thought likely to improve the foam behavior of the aforementioned monoalkylbenzene sulfonate detergents have been tried in the past, in most instances, without success. Moreover, the costs of many of the proposed additives were too high, rendering their application in the amounts adequate to attain the desired improvement uneconomical. Higher saturated aliphatic alcohols, for instance, normal C₈—C₁₈ saturated aliphatic alcohols have been reported in the art as "suds boosters" for alkyl sulfate detergents and sulfated and sulfonated aliphatic acyl-containing detergents, such as C₈—C₂₂ fatty acid monoglyceride monosulfates. However, addition of these alcohols to branched-chain monoalkylbenzene sulfonate detergent compositions failed to occasion any significant improvement in the stability, quality and persistence of the foam. As an example, addition of 10% by weight of normal hexadecanol to a C₁₂—C₁₅ branched-chain monoalkylbenzene sulfonate detergent appears to exert a defoaming action in an agitated aqueous solution thereof, rather than to have a stabilizing effect on the foam. The same ineffectiveness with respect to the improvement of foam stability, quality and persistence of the aforesaid sulfonate detergents is observed with other higher saturated aliphatic alcohols, such as n-dodecanol, n-tetradecanol, n-octadecanol and corre-

2

sponding 1,2-glycols, for instance, n-hexadecane 1,2-glycol.

It was, therefore, entirely unexpected to discover that the foam of dilute aqueous solutions of branched-chain C₉—C₁₅ monoalkylbenzene sulfonates in the range of concentrations from 0.05 to 0.5%, conventional in the laundering art, can be markedly improved in quality and rendered stable and persistent under the conditions of agitation by combining these monoalkylbenzene sulfonates with from about 2 to about 20% by weight thereof, of a sulfonated C₁₀—C₁₈ (and preferably C₁₂—C₁₈) saturated fatty acid anilide (N-acyl sulfonilate), and further combining the resulting mixture of sulfonates with from about 2 to about 20% by weight thereof, of a saturated aliphatic alcohol from the group consisting of C₁₄—C₁₆ normal monohydric aliphatic alcohols and 1,2-glycols. When detergent compositions consisting essentially of the aforementioned three components: alkylbenzene sulfonate, N-acyl sulfonilate and an aliphatic saturated alcohol or 1,2-glycol, within the foregoing ranges of proportions, are dissolved in aqueous solutions for the purpose of washing soiled articles such as fabrics, clothes and dishes, a stable, good-quality foam is produced and persists despite the vigorous agitation of the washing solution in the corresponding machine or device. In view of the low solubility in water of sulfonated higher saturated fatty acid anilides (N-acyl sulfonilates) of the order of less than 0.1% at room temperature, they produce a very low foam or no foam at all, either alone or in combination with higher saturated aliphatic alcohols, upon being dissolved in water and agitation. When added to branched-chain C₉—C₁₅ monoalkylbenzene sulfonates the C₁₀—C₁₈ N-acyl sulfonilates fail completely to enhance the quality, stability or persistence of the foam of aqueous solutions of the resulting blends. Therefore, the improvement in foam performance of branched-chain C₉—C₁₅ monoalkylbenzene sulfonate detergents achieved by combining with them N-acyl sulfonilates and saturated C₁₄—C₁₆ aliphatic alcohols is altogether surprising.

The alkylbenzene sulfonate components of the improved composition of our invention are branched-chain C₉—C₁₅ monoalkylbenzene sulfonates, and predominantly the C₁₂—C₁₅ monoalkylbenzene sulfonates. These sulfonate materials are manufactured in accordance with the procedures known in the art, the process described in the U. S. Patent 2,477,383 to A. H. Lewis being particularly suitable. Although any water-soluble, detergent branched-chain alkylbenzene sulfonate may be employed in formulating the compositions of our invention, sodium salts are usually preferred.

The sulfonilate components are prepared in any convenient manner, for instance, by reacting a suitable fatty acid with aniline or a methyl-substituted aniline, sulfonating the reaction product and neutralizing to form a salt, sodium salts being again preferred. The C₁₀—C₁₈ saturated straight-chain N-acyl sulfonilates are moderately crystalline, flaky materials, varying in color from amber to white in accordance with the degree of their purity. Typical representatives of these sulfonilates are: N-lauroyl sulfonilate, N-palmitoyl sulfonilate, N-stearoyl-N-methyl sulfonilate, and the like.

The saturated normal aliphatic alcohol component may be either a C₁₄—C₁₆ straight-chain monohydric alcohol or a C₁₄—C₁₆ straight-chain 1,2-glycol.

The actual formulation of the improved detergent compositions of our invention offers no particular problem. The three components are slurried together, and the slurry is reduced to the desired form or particle size by conventional drying techniques.

As with other anionic detergent compositions, the improved composition of our invention can be "built" by employing the conventional detergent salt builders of the

trade, either neutral salts of strong inorganic acids, such as sodium chloride, potassium chloride and sodium sulfate, or alkaline salts of weak inorganic acids, such as sodium carbonate, sodium tripolyphosphate, tetrasodium pyrophosphate, sodium silicate, borax, etc. From 60 to 90% by weight of these builders, preferably as sodium salts, may be present in each 100 parts by weight of the finished detergent formulation. Of course, some sodium sulfate builder is present with the alkyl-benzene sulfonate component because of the usual methods for the preparation of this latter. Other conventional additives to detergent formulations, such as anti-caking agents, optical bleaches, corrosion inhibitors (e. g., Na_2SiO_3), extenders and preventives of soil redeposition (e. g., carboxymethyl cellulose or derivatives of oxidized cellulose), skin emollients and anti-irritants (e. g., N-alkylglycines and N-alkyl diglycines), perfume and coloring may be present in small amounts, rarely exceeding a total of 5% by weight, based on the solids content of the formulation, and in all events in such amounts as not to interfere with the improved foam performance.

The superior foam performance of the detergent composition of the invention was verified by testing the foam stability and quality of aqueous solutions thereof in the laboratory. In a representative test series, the essential three components: the alkylbenzene sulfonate, the N-acyl sulfonate and the aliphatic alcohol took up from about 20 to 22% by weight of each 100 parts of the dried built detergent formulation. The builders and additives

6 cetyl alcohol being used in the larger proportion of the runs because of its ready availability.

Water from the laboratory tap was employed to prepare test solutions of 0.15% concentration. This water had a hardness of 50 p. p. m., calculated as CaCO_3 and MgCO_3 in a weight ratio of 2:1. In each test run, 500 ml. of the solution at 120° F. was introduced into a two-liter beaker, and the contents of the beaker were then agitated by means of a propeller-type stirrer for one minute. At the end of this period, foam height in millimeters was measured and the foam quality and stability observed. The agitation was resumed and, after fifteen minutes, the foam height, quality and stability were again determined.

15 Stability was rated by watching the rate of foam decay under mechanical stress, namely, when blowing on a small volume of foam gently with air. Where the surface bubbles of the foam withstood blowing and did not collapse, the stability was rated Good. Where the foam collapsed rapidly, the stability was rated Poor. Intermediate stabilities were rated as Fair.

20 Quality of the foam was considered to be Good when it was made up of small-size dense-bodied bubbles of a high bulk viscosity and presented a uniformly white, opaque texture. Foam of Poor quality was formed by large-size bubbles, was lacy, grayish in color, relatively transparent and displayed a low bulk viscosity. Foams intermediate in quality between Poor and Good were rated Fair.

Foam evaluation tests

¹ Mixture of C₁₄-C₁₈ aliphatic alcohols derived from tallow by catalytic hydrogenation, C₁₈ alcohol being the major component

were: 30% of sodium tripolyphosphate, 20% of tetrasodium pyrophosphate, 5% of "N" grade liquid commercial sodium silicate and the remainder to make up 100% by weight was sodium sulfate. In all tests, sodium C₁₂-C₁₅ polypropylene benzene sulfonate was employed as a typical branched-chain alkylbenzene sulfonate detergent whose foam ordinarily lacks the required quality and stability. N-lauroyl sulfonate, N-stearoyl sulfonate and N-stearoyl, N-methyl sulfonate were selected as typical representatives of the operative group of C₁₀-C₁₈ N-acyl sulfonates and combined with the alkylbenzene sulfonate component in the proportions within the range specified hereinbefore. Saturated aliphatic alcohols, both the operative C₁₄-C₁₆ alcohols and (for the purpose of comparison) the inoperative ones outside the C₁₄-C₁₆ were employed in the proportions specified hereinabove,

65 The tabulated data unambiguously illustrate the superior foam performance of the three-component detergent mixture of the present invention over the formulations in which the only active detergent component is a branched-chain alkylbenzene sulfonate (run No. 16), over formulations in which a saturated C₁₄-C₁₆ normal aliphatic alcohol is added to the detergent alkylbenzene sulfonate employed alone (run No. 26), and over the formulations in which a C₁₆-C₁₈ N-acyl sulfonate in amounts ranging from about 2 to about 20% by weight is added to the alkylbenzene sulfonate detergent in the absence of the saturated aliphatic C₁₄-C₁₆ alcohol or 1,2-glycols (runs Nos. 6, 7 and 14). Sulfonates employed alone, owing to their low solubility, are totally incapable of forming the desired suds. Their combinations with C₁₄-C₁₆ aliphatic alcohols are likewise incapable

of satisfactory foam performance (run No. 28). When alcohols other than the saturated C_{14} - C_{16} alcohols were employed (runs Nos. 4, 17 and 18), the suds were unsatisfactory both in quality and in stability. Furthermore, whenever in the three-component combination of branched-chain alkylbenzene sulfonate, sulfanilate and alcohol, the sulfanilate or the alcohol components are present in amounts outside the preferred operative ranges specified hereinbefore, a poor foam performance invariably results (runs Nos. 2, 5, 8, 10, 11 and 21).

The three-component detergent formulation prepared in accordance with the invention produces stable, good-quality suds when employed in dilute aqueous solutions to wash soiled laundry in automatic and non-automatic agitator-type washing machines, and these suds persist throughout the complete washing cycle, usually of at least 20 minutes' duration. At the same time a very satisfactory cleansing action is achieved. A similar effectiveness with respect to the foam stability and persistence and a satisfactory cleansing action is achieved in employing the formulation of this invention to wash dishes in automatic dishwashers.

We claim:

1. A built detergent composition of superior foam characteristics consisting essentially, by weight, of about 25 100 parts of a branched chain C_9 - C_{15} alkylbenzene sul-

fonate sodium salt detergent, about 2 to 20 parts of a saturated aliphatic alcohol selected from the group consisting of straight chain C_{14} - C_{16} saturated monohydric alcohols and 1,2-glycols, from about 2 to 20 parts of an N-acyl sulfonilate of the general formula

wherein R is a straight chain alkyl group of 9 to 17 carbon atoms and R' is a radical selected from the group consisting of hydrogen and methyl radicals, and about 60% to 90% based on said built detergent composition of inorganic sodium salt builders.

2. Composition according to claim 1 wherein the alcohol is a straight chain C_{14} - C_{16} saturated monohydric alcohol.

3. Composition according to claim 1 wherein R' is hydrogen.
